UNITED STATES PATENT OFFICE.

FRANCIS M. BARTON, OF CHICAGO, ILLINOIS.

ROD SUPPORT.

Application filed April 11, 1928 Serial No. 269,058.

The invention relates to rod supports or chairs and more particularly to those supports which are made by bending strips of wire and are employed in the formation and construction of concrete structures to space and position reinforcing rods preparatory to pouring the concrete in the molds and around the bars.

One object of the present invention is to provide a support of this character which is of an improved construction and is so formed that the bending operation may be accomplished in a simple manner and with a minimum number of steps, thus facilitating manufacture and reducing the cost of the finished product.

Another object of the invention is to provide a wire support or chair for retaining in place concrete reinforcing bars which is staple and rigid and permits the concrete to be poured readily and completely there-around.

Other objects will be manifest from the detailed description hereafter.

The invention consists in the several novel features hereinafter set forth and more particularly defined by the claims at the conclusion hereof.

In the drawing which accompanies and forms a part of this specification or disclosure and in which like numerals of reference denote like parts throughout the several views:

Figure 1 is a perspective, showing the manner in which the supports are used to space the reinforcing bars from the concrete mold;

Figure 2 is a side elevation of a support embodying the invention;

Figure 3 is a front view;

Figure 4 is a perspective of a U-shaped strip of wire from which the support is bent; and

Figure 5 is a view similar to Figure 4, showing the manner in which the end of the wire strip embodying the cross bar is bent to form the legs of the support and the bar rest.

The invention is exemplified in a wire support or chair for supporting a cross-bar *a* in spaced relation with respect to a concrete form or mold (not shown). This cross-rod in turn supports a plurality of metallic reinforcing rods or bars *b* so that the latter will be properly positioned and retained during the concrete pouring operation, as well understood in the art. As shown in Figure 1, two chairs or supports are preferably used

to sustain the cross-bar *a*, said supports being arranged adjacent the ends of the cross-bar and to face one another. The concrete is poured into the mold and around the supports and reinforcing bars in any suitable manner. As soon as it sets, the metallic parts which are embedded therein operate as reinforcing members.

The wire chair or support which forms the subject matter of the present invention comprises a pair of front legs 10, a pair of rear legs 11 and a cross member 12 which extends between and connects the front legs 10 and forms a rest for the cross-bar *a*. The front legs 10 are parallel so that the lower ends thereof are spaced apart the same distance as the upper ends. Each of these legs consists of a member 13 which is doubled back upon itself to form a shorter member 14.

The bends or loops 15 which connect the members 13 and 14 are adapted to rest upon the mold and operate as feet. These loops extend at right angles to the plane in which the members 13 lie with the result that the members 14 are disposed parallel with and directly in front of said members 13 as contradistinguished from being in transverse alignment or angled outwardly or inwardly. The upper ends of the short members 14 terminate approximately half way between the midpoints and outer ends of the members 13 and are connected to the cross member 12 by integral right angle portions or bends 16. A characteristic of positioning the loops 15 in the manner set forth is that the members 14, as well as the connecting bends or portions 16, are directly in front of the leg-members 13. Since the legs 10 slant rearwardly, as shown in Figures 1 and 2, this arrangement operates to effectively lock the cross-bar and members 14 against rearward movement relatively to the members 13. In this manner the concrete reinforcing bars *a* and *b* are efficiently supported.

The cross-member 12 is preferably made so as to substantially correspond in length to the diameter of the cross-bar *a*. The upper or extended portions of the members 13 operate as sides for the cross-member 12 and prevent lateral displacement of the bar *a*. The rear legs 11 are joined to the upper ends of the members 13 by integral connecting portions 17 which are bent so that the legs extend downwardly and rearwardly and also outwardly, as shown in Figure 3, to give lateral stability to the support. By having the front

legs 10 parallel and comparatively close together and the rear legs project outwardly in the manner set forth, the support is substantially in the form of a pyramid and is extremely rigid.

The chair or support is bent from a single U-shaped strip of wire having parallel side members (Figure 4). The first step of the manufacturing or forming operation consists in doubling back upon itself the end of the wire strip that embodies the cross member. This one bending step serves to position the cross member 12 and forms the front legs 10. The distal ends of the side members of the U-shaped wire strip are then bent so as to extend outwardly and at an acute angle with respect to the end that is doubled back and to form the rear legs 11. This second step completes the manufacturing operation. Since only a U-shaped strip of wire is used and there are only two bending steps, it is manifest that the cost of manufacture is comparatively small. By making the first bend at different places, the height of the cross-bar may be varied or positioned as desired.

The support or chair disclosed herein is not only capable of being produced at a low cost, but because of its specific construction is efficient and operates to effectively support relatively heavy reinforcing bars.

The invention is not to be understood as restricted to the details set forth, since these may be modified within the scope of the ap-

35
pended claims, without departing from the spirit and scope of the invention.

Having thus described the invention, what I claim as new and desire to secure by Letters Patent, is:

1. A support for a reinforcing bar, formed from a single strip of wire and comprising a pair of substantially parallel legs, each consisting of a member having one end doubled back upon itself to form a second member directly in front thereof, and a cross member joined to the second members by bent portions disposed directly in front of andlapping the front faces of the other members, said cross-bar being operative to space the legs apart and support the bar.

2. A support for a reinforcing bar, formed from a single strip of wire and comprising a pair of substantially parallel front legs, each consisting of a member having its lower end doubled back upon itself to form a second member in front thereof, a pair of legs joined to the upper ends of the first mentioned members and extending rearwardly and outwardly, and a comparatively short cross member joined to the upper ends of the second members, said cross bar being operative to space the front legs close together and support the bar.
